(57) **CLAIM**

The ornamental design for a seashell couch, as shown and described.

DESCRIPTION

FIG. 1 is a right front perspective view of a seashell couch showing my design;

FIG. 2 is a front view of the embodiment of the invention shown in FIG. 1;

FIG. 3 is a top plan view of the embodiment of the invention shown in FIG. 1;

FIG. 4 is an end view of the right side of the embodiment of the invention shown in FIG. 1;

FIG. 5 is an end view of the left side of the embodiment of the invention shown in FIG. 1; and,

FIG. 6 is a back view of the embodiment of the invention shown in FIG. 1.

The fragmented cross-hatching is understood to represent fabric and would be continuous throughout the circumscribed areas.
